Attorney

UNITED STATES PATENT OFFICE.

WILLIAM J. WELCH, OF GRANT CITY, MISSOURI.

DISK PLOW.

Application filed July 10, 1923. Serial No. 650,616.

To all whom it may concern:

Be it known that I, WILLIAM J. WELCH, a citizen of the United States, residing at Grant City, in the county of Worth and State of Missouri, have invented certain new and useful Improvements in Disk Plows, of which the following is a specification.

This invention relates to an improved 10 disk plow for road excavators.

The primary object of the invention is to provide a fin cutter for stationary disk plows, by means of which the furrow is cut centrally in a direction parallel with the 15 line of advance of the disk, whereby said furrow will be effectively severed for preventing clogging of the elevator of the excavator.

Another object is to provide a fin cutter of 20 the above kind which is rotarily adjustable relative to the disk plow so as to permit proper positioning of said cutter when the disk plow is rotarily adjusted to present a new cutting edge thereon.

25 Briefly described, the invention embodies the provision of a fin cutter or blade on the upper surface of the usual stationary disk plow of a road excavator, which fin cutter has an inclined upper cutting edge, 30 for providing a longitudinal cut in the furrow.

Other objects of the invention will appear as the nature of the invention is better understood, and the same consists in 35 the novel form, combination and arrangement of parts hereinafter more fully described, shown in the accompanying drawing and claimed.

In the drawing, wherein like reference 40 characters indicate corresponding parts throughout the several views,

Figure 1 is a plan view of a stationary plow having a fin cutter attached thereto in accordance with the present invention,

45 Figure 2 is a sectional view taken substantially on line 2-2 of Figure 1, and

Figure 3 is a perspective view of the fin cutter detached.

Referring more in detail to the views, 5 50 indicates a well known type of concavo-convex stationary disk plow adapted to be suitably carried by the excavator in such

manner that the same is held against rotation when in use, although capable of being rotarily adjusted from time to time 55 for presenting a new cutting edge, when desired.

In accordance with the present invention, a fin cutter 7 having a flange 8 along its inner edge, is provided, adapted to flatly contact with the upper or inner surface of the disk 5, when disposed radially of the latter as shown in Figure 1. It will be seen from Figure 2, that the fin cutter or blade 7 has its upper or longitudinal edge inclined by tapering the blade gradually narrower toward the center of the disk or toward the inner end of the blade.

In order to permit the position of the blade 7 to be changed whenever the disk 70 5 is rotarily adjusted, so that said blade 7 will at all times be parallel with line of advance of the excavator, said blade is preferably attached as shown by means of a bolt 9 extending through the inner end of the 75 flange 8 and through the center of the disk, and by means of another bolt 9' extending through the outer end of the flange 8 and adapted to enter the desired one of the series of equally spaced marginal openings 10 80 provided in the disk 5. By means of this construction, it will be seen that when the bolt 9 is loosened, and the bolt 9' is removed, the blade 7 may be rotated relative to the disk to the desired position, after which, the 85 bolt 9 may be again tightened and the bolt 9' again inserted through the opening in the outer end of the flange 8 and the new opening 10 which has been alined therewith.

90 By means of this construction, it will be seen that the fin cutter is detachably, adjustably and rigidly secured to the disk in a simple and effective manner.

In use, the fin cutter 7 is positioned at the 95 rear side or top of the disk 5 so as to cut the furrow as the latter passes to the elevator of the excavator. Also, as the fin cutter or blade 7 is disposed radially of the disk and parallel with the line of travel of the latter, it will cut the furrow substantially 100 centrally in advance of the elevator, so that the latter will not become clogged during the operation of the excavator.

From the foregoing description, it is believed that the construction and operation as well as the advantages of the present invention will be readily understood and appreciated by those skilled in the art.

Minor changes may be made without departing from the spirit and scope of the invention as claimed.

What I claim as new is:—

- 10 1. A plow disk comprising a concavo-convex circular body, and an outstanding fin applied to the concaved side of the body

and disposed radially from the central portion to the peripheral edge of the body.

2. A plow disk structure comprising a 15 concavo-convex circular body, a fin having a flange applied to the concaved surface of the body, the fin being disposed from the central to the peripheral portion of the body.

20

In testimony whereof I affix my signature.

WILLIAM J. WELCH.
